Primary Examiner — Marianne Pandozzi(74) *Attorney, Agent, or Firm* — Abelman, Frayne & Schwab(57) **CLAIM**

The ornamental design for a drinking cup, as shown and described.

DESCRIPTION

FIG. 1 is a top, left side and front perspective view showing a drinking cup of our new invention,

FIG. 2 is a front elevation view thereof,

FIG. 3 is a right side elevation view thereof,

FIG. 4 is a left side elevation view thereof,

FIG. 5 is a rear elevation view thereof,

FIG. 6 is a top plan view thereof; and,

FIG. 7 is a bottom plan view thereof.

The broken lines in the drawings are included for the purpose of illustration and form no part of the claimed design.
